US0D1037064S

(12) United States Design Patent (10) Patent No.: US D1,037,064 S
(45) Date of Patent:  Jul. 30, 2024

(54) PLANTER

- (71) Applicant: Apple Inc., Cupertino, CA (US)
- (72) Inventors: Jonathan P. Siegel, San Francisco, CA (US); Christopher M. Green, Woodside, CA (US); Stefan Behling, London (GB); David Summerfield, London (GB); James McGrath, Cupertino, CA (US); Christopher Daniel Peak, Oakland, CA (US); Patrick O'Brien, San Jose, CA (US); Jennifer Ross Wynn, San Francisco, CA (US); Andrea Fender Badgley, San Francisco, CA (US); Richard P. Howarth, San Francisco, CA (US); Rafe Bertram, London (GB); John De Maio, Cupertino, CA (US); Susana Varela De Sagarra, London (GB); Raoul Skrein Bumballa, London (GB); Neil Bancroft, London (GB); Charlotte Hofstetter, San Francisco, CA (US); Afrodit Kavallieraki, London (GB)

- (73) Assignee: Apple Inc., Cupertino, CA (US)

- () Term: 15 Years

- (21) Appl. No.: 29/830,167

- (22) Filed: Mar. 10, 2022

Related U.S. Application Data

- (63) Continuation of application No. 29/736,070, filed on May 27, 2020, now Pat. No. Des. 947,063, which is

CLAIM

The ornamental design for a planter, as shown and described.

DESCRIPTION

FIG. 1 is a top front perspective view of a planter showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the planter that form no part of the claimed design.

1 Claim, 7 Drawing Sheets

Related U.S. Application Data

a continuation of application No. 29/642,440, filed on Mar. 29, 2018, now Pat. No. Des. 887,305, which is a continuation of application No. 29/577,172, filed on Sep. 9, 2016, now Pat. No. Des. 814,345, which is a continuation of application No. 29/522,921, filed on Apr. 3, 2015, now Pat. No. Des. 766,127, and a continuation of application No. 29/517,034, filed on Feb. 9, 2015, now Pat. No. Des. 769,148, said application No. 29/522,921 is a continuation-in-part of application No. 29/517,034, filed on Feb. 9, 2015, now Pat. No. Des. 769,148.
